UNITED STATES PATENT OFFICE.

WILLIAM S. WARD, OF PLANTSVILLE, CONNECTICUT, ASSIGNOR OF ONE-HALF TO EDWARD W. TWICHELL, OF SAME PLACE.

DESIGN FOR A BICYCLE SHAFT AND CRANK.

SPECIFICATION forming part of Design No. 26,031, dated September 15, 1896.

Application filed July 26, 1896. Serial No. 600,558. Term of patent 14 years.

To all whom it may concern:

Be it known that I, WILLIAM S. WARD, a citizen of the United States residing at Plantsville, in the county of Hartford and State of Connecticut, have invented and produced a new and original Design for a Bicycle Shaft and Crank, of which the following is a specification, reference being had to the accompanying drawings, in which—

Figure 1 is a side elevation of a bicycle shaft and crank, showing my design. Fig. 2 is an end view of the same, showing the inner face of the crank.

In my design the main portion of the shaft is cylindrical and has formed on it at one end two arms and the crank.

A designates the main portion or cylindrical body of the shaft, 3 an arm-hub with two arms 4 radiating therefrom, and B is the crank formed on the extreme end of the shaft and radiating therefrom at a point midway between the arms 4, and so as to extend in the opposite direction therefrom. The arms, as seen in the position illustrated in Fig. 2, are

the widest near their hub and gradually taper toward their outer end. Their broad sides are rounded, so that the body of the arms is substantially in the form of an ellipse. Near their outer ends they are provided with an abrupt offset 5 on their inner face, from which offset the outer ends of the arms are straight on all sides in the form of plates 8, the flat outer sides of said plates being substantially a continuation of the outer broad side of the arms, but changed from the rounded form to a flat form. The crank B is slightly tapering and is mainly round in cross-section. Its outer end is provided with a head 6, as shown, and upon its inside is a pyramidal projection 7, with a ledge 9 on that side which is nearest the shaft.

What I claim is—

The design for a bicycle shaft and crank substantially as herein shown and described.

WILLIAM S. WARD.
